(57) **CLAIM**

The ornamental design for a flowerpot, as shown and described.

DESCRIPTION

FIG. 1 is an isometric view of the flowerpot showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The long and short broken lines in FIG. 6 define the bounds of the claimed design and form no part thereof. The evenly spaced broken lines in FIG. 6 represent a portion of the flowerpot that forms no part of the claimed design.
